(57) **CLAIM**

The ornamental design for a front mudguard for a motorcycle, as shown and described.

DESCRIPTION

FIG. 1 is a side elevational view of one side of a front mudguard for a motorcycle showing one embodiment of our new design;

FIG. 2 is a side elevational view of the other side thereof;

FIG. 3 is a front elevational view thereof;

FIG. 4 is a rear elevational view thereof;

FIG. 5 is a top perspective view thereof;

FIG. 6 is a bottom plan view thereof;

FIG. 7 is a front perspective view thereof;

FIG. 8 is a rear perspective view thereof;

FIG. 9 is a side elevational view of one side of a front mudguard for a motorcycle showing another embodiment of our new design, the opposite side being a mirror image;

FIG. 10 is a front elevational view thereof;

FIG. 11 is a rear elevational view thereof;

FIG. 12 is a top perspective view thereof;

FIG. 13 is a bottom plan view thereof;

FIG. 14 is a front perspective view thereof;

FIG. 15 is a rear perspective view thereof;

FIG. 16 is a side elevational view of Embodiment 1 on a reduced scale, shown in position of use on a motorcycle, which is shown in broken lines for illustrative purposes only and forms no part of the claimed design; and,

FIG. 17 is a front perspective view of FIG. 16.
